ELECTRON DISCHARGE DEVICE OF THE
VELOCITY MODULATION TYPELeonard J. Davies, Leonard Rushforth, William
D. Sinclair, and Christopher J. Milner, Rugby,
England, assignors to General Electric Com-
pany, a corporation of New YorkApplication December 18, 1946, Serial No. 717,060
In Great Britain October 29, 1941Section 1, Public Law 690, August 8, 1946
Patent expires October 29, 1961

3 Claims. (Cl. 315—6)

1

Our invention relates to electron discharge devices of the velocity modulation type in which at least one resonating chamber is employed and in which high frequency electrical oscillations are developed by reaction with an electron beam.

The resonating chambers employed in such devices may consist of hollow annular members having a circumferential gap along their portions of minimum diameter. The electron beam is projected across the gap and coaxially with the chamber. The chamber may be of generally circular or rectangular shape in cross-section as desired. In some such devices two or more resonating chambers are spaced along in coaxial relation therewith.

Manufacturing difficulties have hitherto been encountered in producing discharge devices embodying such resonating chambers. The resonators frequently have been constructed by machining two or more parts from solid metal, the parts being assembled to form the resonating chamber. The envelope of the device is then completed by means of two sections of a glass envelope which are sealed coaxially on to the resonating chamber at each end thereof, one of them carrying the electron gun and the other the electron collecting electrode. It is important that the electron gun be so positioned that the beam is accurately coaxial with the resonating chamber or chambers. It is also desirable to provide an elongated hollow collecting electrode which is coaxial with the chamber.

It is an object of the present invention to provide a construction which facilitates the production and accurate assembly of such devices.

It is a further object of our invention to provide an improved collecting electrode and mounting therefor.

In accordance with the illustrated embodiment of the invention the resonating chamber is made by assembling two or more parts within a hollow casing to which at one end either the electron gun or collecting electrode has been previously sealed and accurately positioned, the device being then completed by sealing an electron collecting electrode or gun respectively to the other end of the casing.

The assemblage of parts constituting the resonating chamber or chambers, if two or more are used, which may previously have been formed into an integral unit, if desired, may be accurately positioned axially within the outer casing by providing an internal shoulder on the casing against which the unit is seated, it being understood that the external diameter of the resonat-

2

ing chamber is equal to, or slightly less than the internal diameter of the casing so that the two are accurately fitted. At one end the casing is then provided with a neck portion tapering to a fine edge to which a cylindrical glass member carrying a stem supporting the electron gun is sealed. At the other end of the casing a collecting electrode comprising an elongated tubular member is supported. The electrode is preferably provided with an internal recess which has a depth equal to several times its diameter to provide a field free region in which the beam is defocussed and which minimizes the liberation of secondary electrons.

Our invention will be better understood by reference to the following description taken in connection with the accompanying drawing, and its scope will be pointed out in the appended claims. In the drawing, the single figure is an elevational view in section of an electric discharge device embodying our invention.

Referring now to the drawing we have shown a velocity modulation electron discharge device comprising an electron-emitting cathode 1, a pair of resonating chambers 2 and 3, and an electron collecting electrode 4. The resonating chambers 2 and 3 are formed by a hollow annular member 5 of circular or rectangular cross-section and arranged back-to-back so as to possess a common intermediate wall 6. The chambers have circumferential gaps 7 and 7' respectively along their portions of substantially minimum diameter, the electron beam being projected across the gaps in a direction coaxially with the resonating chambers. The electron beam emanating from the cathode 1 is focussed by an electron gun including electrodes 8 and 9 into a narrow beam indicated by interrupted lines 10, which is projected across the gaps, and after passage through the gaps is received by the collecting electrode 4. The resonating chambers 2 and 3 are thus spaced axially along the beam.

As is now well known, the electron beam during its passage across the gap 7 (if its mean velocity is suitably adjusted to the width of the gap), causes oscillations to be produced in the resonating chamber 2, the frequency of which is dependent upon the physical dimensions of the chamber including the gap 7, causing high frequency potential variations to occur across the gap 7, which produce velocity modulation of the beam 10. The velocity modulated beam passing across the gap 7' induces oscillations in the resonating chamber 3, the oscillations in the two

chambers being caused to reinforce one another by means of the coupling loop 11. The chambers 2 and 3 are further coupled by means of an array of apertures 6" in the transverse wall 6, the apertures being located on a circle the diameter of which is approximately the mean diameter of the resonating chambers.

Since the frequency of the oscillations generated in the resonating chambers 2 and 3 is determined by the physical dimensions of those chambers, as above pointed out, and when the oscillations are of a very high frequency, it is important that the dimensions of the chambers should be accurately controlled within very fine limits since the resonating frequency of both chambers should be the same. The chambers are accordingly constructed in separable parts, each of which can be accurately machined, and these parts are inserted in an outer casing 12 forming part of the envelope of the device. The casing 12 includes a main body portion, the inner diameter of which is equal to the outer diameter of the resonating chambers, provided with an internal shoulder 13, from which extends upwardly a cylindrical portion 14 terminating in a tapered rim 15 to which is sealed a stem 16 of glass or like insulating material on which has previously been mounted the electron gun including cathode 1 and electrodes 8 and 9. The gun may thus be accurately positioned coaxially with the portion 14 of the casing.

The two resonating chambers are formed of an outer cylindrical shell 5 having the transverse wall 6 above mentioned and two end walls 17 and 18 respectively. The wall 6 has a central aperture defined by tubular extensions 6' extending from opposed faces of the wall 6. Similarly the end walls 17, 18 have tubular extensions 17', 18' defining central apertures therein. These three parts may be previously assembled with the members 17 and 18 received in recesses machined in the opposite ends of cylinder 5 so that their relative positions can be accurately controlled, and the assembled parts are then inserted into the casing from the lower end thereof until the wall 17 is against the internal shoulder 13. The parts are secured together by means of a ring 19 which may be threaded, if desired.

The collecting electrode 4 is provided with a transverse flange 20 which is received in a recess at the lower end of the casing 12, thus completing the assembly of the device. If it is desired to operate the collecting electrode 4 at a direct current potential different from that of the resonant chambers, the flange 20 may be a body of glass. The previously assembled output lead 21 is received in a transverse aperture in the wall of the casing 12 and resonating chamber 3, and is secured in position, as by brazing. The output lead is coupled into chamber 3 by a loop 21' and is sealed in a vacuum tight relation to the envelope by means of a body of glass 22.

As indicated, the resonating chambers may be provided with a jacket 24 and the collecting electrode with the jacket 25, through both of which jackets water may be circulated for cooling purposes.

If desired, the parts may have the joints made vacuum tight in one operation after assembly by providing a brazing metal in contact with each of the joints and baking the whole assembly at a temperature necessary to fuse the brazing metal at all joints simultaneously.

The electron collecting electrode 4 is preferably recessed to a depth several times the di-

ameter to provide a space of zero electrostatic field which the beam enters and travels for a considerable distance thereby becoming defocussed due to the mutual repulsion of the electrons. The electrons are thus collected more uniformly on various parts of the internal surface of the collecting electrode and local heating is thereby avoided. There is also no field to assist in the liberation of secondary electrons and the emission of such electrons is minimized and most of those liberated are collected on the walls of the collecting electrode.

While the invention has been described in connection with a device employing two resonating chambers, it is evident that one such chamber only, or more than two may be utilized. When only one resonating chamber is used, the output lead will be coupled in to that chamber, while with three or more chambers, the output lead will preferably be coupled in to that nearest the collecting electrode.

In operation the resonating chambers and the collecting electrode, which are all electrically at a common potential, may be maintained at a high potential with reference to the cathode and thus form the final anode of the electron gun. Preferably the cathode is maintained at a negative potential, the casing being at ground potential.

While we have described and illustrated a particular embodiment of our invention, it will be obvious to those skilled in the art that changes and modifications may be made without departing from our invention in its broader aspects and we therefore aim in the appended claims to cover all such changes and modifications as fall within the true spirit and scope of our invention.

What we claim as new and desire to secure by Letters Patent of the United States is:

1. An electric discharge device of the velocity modulation type including a cavity resonator provided by a plurality of cooperating parts, a hollow metal casing forming a part of an hermetically sealed envelope of the device and having an inwardly directed shoulder at one end, said cooperating parts being received within said casing and axially positioned by said shoulder, a hollow elongated electron gun and a collecting electrode sealed respectively to the opposite ends of said casing to complete the envelope of the device.
2. An electric discharge of the velocity modulation type comprising a hollow cylindrical casing forming a part of an hermetically sealed envelope of the device, an electron gun sealed to one end of said casing and a hollow elongated electron collecting electrode sealed to the other end of said casing, a hollow cylindrical shell having its external diameter substantially equal to the internal diameter of said casing, said shell being positioned within said casing and having a transverse wall with a central aperture therethrough defined by tubular extensions extending from opposite faces of said wall and end walls for said shell each having a tubular extension defining a central aperture, said shell and end walls forming a pair of axially spaced cavity resonators, the space between the adjacent edges of the tubular extensions from the transverse and end walls providing gaps across which a beam of electrons from the electron gun is projected.
3. An electric discharge of the velocity modulation type comprising a hollow cylindrical casing forming a part of an hermetically sealed envelope of the device, an electron gun sealed to one end of said casing and a hollow elongated electron

collecting electrode sealed to the other end of said casing, a hollow cylindrical shell having its external diameter substantially equal to the inner diameter of said casing, said shell being positioned within said casing and having a transverse wall with a central aperture therethrough, an end wall for said shell and having a central aperture therethrough, one of said walls having a tubular extension surrounding the central aperture and extending into the resonator to define with the other apertured wall a gap across which a beam of electrons passes from said gun to said collecting electrode.

Certificate of Correction

Patent No. 2,512,887

June 27, 1950

LEONARD J. DAVIES ET AL.

It is hereby certified that error appears in the printed specification of the above numbered patent requiring correction as follows:

Column 4, lines 47 and 48, strike out the words "a hollow elongated electron gun and a" and insert instead *an electron gun and an elongated*;
and that the said Letters Patent should be read as corrected above, so that the same may conform to the record of the case in the Patent Office.

Signed and sealed this 10th day of October, A. D. 1950.
